UNITED STATES PATENT OFFICE.

FRANCIS M. HESS, OF WHITING, INDIANA.

METHOD OF AND APPARATUS FOR CRACKING OIL.

Application filed January 24, 1923. Serial No. 614,555.

This invention relates to methods of and apparatus for cracking oils, and has reference more particularly to an improved method of and apparatus for cracking oil with the aid of gases produced by a restricted internal combustion of the residuum product of distillation.

It is known that extraneous gas added to the vapors in a cracking unit is an aid to cracking if said gas is rich in hydrogen and hydrogen compounds. My present invention is based on this principle, and the leading objects of the invention are, first, to provide an improved method and apparatus for efficiently burning a portion of the residuum of the distillation process, which constitutes a very suitable fuel oil, to generate a gas rich in hydrogen and hydrogen compounds, which gas is admixed with the vapors in the cracking unit to aid the cracking of the oil; to provide a method and apparatus whereby the heat resulting from the combustion of the residuum, as well as the heat of the portion of the residuum that is not burned, may be utilized to heat the cracking unit itself; to restrict the combustion of the residuum within such temperature limits that gases only are produced (with possibly a negligible amount of ash); and to provide a complete unitary apparatus for both cracking the oil and generating the gas employed to aid in the cracking in a continuous operation, and wherein both the cracking unit or still and the gas producer operate under the same internal pressure.

The cracking process herein disclosed is based on the cracking process disclosed and claimed in an application filed by me June 7, 1922, Serial No. 566,470, with the addition of a gas producer connected to the cracking unit and operating to generate a gas rich in hydrogen and hydrogen compounds for both partially heating the heating plates of the still and mingling with the generated vapors to aid in the cracking of the latter.

In the accompanying drawing I have illustrated a complete apparatus capable of carrying out my improved process of oil cracking with the aid of restricted internal combustion and embodying in a practical and preferred form the novel structural features of my present invention; and referring thereto—

Fig. 1 is an elevation partly in vertical section, illustrating a complete plan or system embodying my invention; and

Fig. 2 is an enlarged cross section through a pair of heating plates of the still taken on the line 2—2 of Fig. 1.

Referring to the drawing, S designates as an entirety a cracking unit or still, R designates as an entirety a residuum tank, and P designates as an entirety a gas producer.

The still.

The cracking unit or still is substantially identical structurally with that described and claimed in a former application filed by me on the 29th day of April, 1922, Serial No. 557,421, and also disclosed in the later application filed June 7, 1922, Serial No. 566,470, and no claim thereto specifically is made herein. 5 designates an upright cylindrical metal tank of sufficient strength to withstand the maximum internal pressures employed in the system, said tank being conveniently supported by hollow feet 6 on any suitable support indicated at 7. Mounted on the lower head of the tank are a pair of parallel upright frame structures designated as an entirety by 8, which constitute supports for a pair of generally W-shaped groups (left and right) of hollow heating plates joined at their convergent ends by hollow headers and internested so as to form between adjacent plates of the two groups a continuous zigzag conduit for the gravity flow of the crude material in a broad thin continuous film or stream from top to bottom. The heating plates of both groups are structurally identical and are best shown in detail in the cross-sectional view, Fig. 2, wherein 9 designates a group of tubes disposed side by side at equally spaced intervals and 10 designates each of a pair of longitudinally corrugated boiler plates which overlie and underlie respectively the tubes 9, and 11 designates rivets uniting the two plates midway between adjacent tubes 9. By this construction is formed a hollow heating plate structure which provides two separate groups of conduits for heating media, namely, the interiors of the tubes 9, and the passages formed between adjacent tubes 9 and the plate sections spanning adjacent tubes. The convergent ends of each connected pair of heating plates are united so as to render the internal conduits

of said plates continuous by the following means. 12 designates a hollow header or manifold that extends transversely of the inner convergent ends of the heating plates 5 and is provided with a central longitudinal partition or bridge plate 13 extending from end to end thereof. Each header carries trunnions 14 that are mounted in the frame uprights 8. The tubes 9 are extended 10 through the inner wall of the header and are fitted into the partition wall 13, whereby said tubes communicate freely with a header chamber 15 on the outer side of the partition wall. The inner wall of the header 12 is formed with apertures at points 15 between adjacent tubes 9, thus throwing the heating plate conduits that lie between adjacent tubes 9 into communication with a header chamber 16 on the inner side of the 20 partition 13.

The outer convergent ends of adjacent header plates are placed in communication with each other by a generally similar header construction, comprising individual headers or manifolds 12' structurally identical with the headers or manifolds 12, and, for the most part, having their respective inner and outer chambers connected by vertical tubes 17 and 18. The headers 12' have at 25 their ends trunnions 14', similar to the trunnions 14 of the headers 12, which trunnions 14' are likewise mounted and supported in the upright frames 8.

The above described structure affords a 30 continuous zigzag multiple tube conduit for the upward flow of a heating agent (gas) through the heating plate tubes 9, the outer header compartments, and the pipes 18 up to certain headers designated by 12^a, from 35 which headers the gas is released and discharged into the vapor chamber (interior of tank 5) through discharge pipes 19. The same structure affords a continuous zigzag multiple tube conduit for the upward flow 40 of residuum from the tank R through a pipe 20 and branch 21 through the remaining superposed heating plate tubes 9, outer header compartments, and pipes 18.

The above described structure also affords 45 a continuous zigzag downflow conduit for other heating media (steam and air in the present instance) delivered through a pipe 22 and branches 23 and 24 to the inner compartments of the headers, the same flowing 50 through said inner compartments, the ducts formed between the tubes 9, and the pipes 17, and thence through pipes 25, 26, and an elbow 27 into a pipe 28 connected to the gas producer as hereinafter described.

To insure the downward and forward flow 55 of the crude material, the longitudinal edges of each plate which forms a part of the trackway or path of the material are turned upwardly, as shown at 29 in Fig. 2 to a level 60 slightly above the height of the headers, thus

preventing lateral spilling or overflow of the crude material, and insuring its continuous downward flow in a zigzag direction over the header at the foot of the plate down onto the next underlying heating plate.

From the outer chambers of the lowermost headers 12' of the two groups of heating plates there extend downwardly branch pipes 30 and 31 both entering the upper end of a vertical pipe 32 which extends down within the pipe 28 and into the top of the residuum tank R. From the outer chambers of the topmost headers 12' of the two groups of heating plates there extend upwardly residuum discharge pipes 33 and 34 75 which are connected into a vertical discharge pipe 35 lying within a pipe 36 through which the crude material is introduced to the still and the generated vapors are discharged 80 from the still.

Directly beneath the lower end of the pipe 36 is a funnel 37, through which the incoming crude material, together with any reflux, is delivered to and overflows a trough 38 90 extending crosswise of the topmost heating plate, by which the crude material with any reflux overflows onto the latter.

The residuum tank.

The residuum tank used in the present 95 apparatus preferably consists of a cylindrical metal tank 40 of ample strength and capacity to serve the purposes of the system; said tank being connected with the bottom of the tank 5 of the still by a pipe 41; the lower head of the tank 5 having a central aperture 42 registering with the upper end of the pipe 41. Mounted within the upper portion of the residuum tank and supported therefrom by hangers 43 is a box 44 forming a seal or trap for the lower end 100 of a gas delivery pipe 45 leading from the gas producer.

The gas producer.

The gas producer, designated generally by the reference character P, is preferably an upright cylindrical structure constructed of boiler plate sufficiently heavy to withstand 110 the maximum internal pressure under which the cracking system is operated. The outer metal casing or shell 46 of the producer is lined with a refractory material 47 to protect it from the high heat; and within the chamber of the producer is a fire grate 48, in the center of which is fitted the lower end 115 of a central upwardly extending pipe 49 leading through the top of the producer, thereby forming an annular chamber which is filled with a body of coke designated by 120 50; the coke being introduced through a side opening 51 closed by a removable cover 52. Above the body of coke is a second perforated plate 53, protected by heat insulating material, on which is supported a body 125 130

of checker work 54. The space in the top of the producer chamber above the checker work communicates through a T-coupling 55 with a pipe 56, which pipe communicates at its other end through a T-coupling 57 with the upper end of the pipe 45. In the pipe 45 is a valve 58. The pipe 49 is connected through an elbow coupling 59 with a horizontal pipe section 60, which latter is connected into the pipe 28. It will be noted that the upper portion of pipe 49, elbow 59 and pipe 60 lie within and extend through the T-coupling 55 and pipe 56.

Within an open space 54' formed in the upper portion of the checker work 54 is located a hollow ring 61 suitably apertured to form an oil spraying device; and connected to the ring 61 is a supply pipe 62 that extends within the main residuum discharge pipe 41 and upwardly of the latter terminating in a flared or cup-shaped upper end 62' lying directly beneath the discharge opening 42 in the bottom of the tank 5. In the pipe 62 is a valve 63. Connected into one end of the pipe 56 is a pipe 64 equipped with a valve 65 and leading to a flue or chimney, (not shown). Connected into the lower end of the pipe 22 are pipes 66 and 67 equipped with valves 68 and 69, respectively. In the bottom of the gas producer, centrally below the grate 48 is a deflector plate 70; and from the bottom of the gas producer a pipe 71 equipped with a valve 72 leads into the residuum tank 40 at a point slightly above the bottom of the latter. Connected into one side of the gas producer at a point below the grate 48 is a short pipe 73 equipped with a valve 74.

I may here state that the term "gas producer" as used herein is not employed in the limited technical sense in which that term is used in the gas making art, but in the broader and more generic sense of an apparatus for generating a gas from and by the splitting up of more complex compounds subjected therein to high temperatures.

Proceeding now to a description of the method of operation, in starting the apparatus the valves 68, 69, 58, 72 and 63 are closed. Valves 65 and 74 are opened, and an oil burner is inserted through the open valve 74 and the pipe 73 into the lower portion of the gas producer below the grate 48. The said burner is supplied with air and oil from an outside source. The oil supplied through the burner is ignited and heating is continued until the body of coke and the checker work are heated to redness, and the temperature in the upper and coolest portion of the checker work is raised to somewhat above 1200° F., so that a high enough temperature is maintained to insure that steam heated in the lower coke zone and dissociated to hydrogen and oxygen cannot be converted back to steam. From this point on the heat-

ed coke acts as a reservoir of heat for the gasifying of the residuum and the generation of hydrogen from steam and as a supply of combustible material when needed. The superposed checker work acts as a secondary reservoir of heat, but at a lower temperature and also as an auxiliary distributing agent for atomized oil issuing from the spray pipe 61.

While the preliminary heating up of the gas producer goes on, the products of combustion escape past the open valve 65 through pipe 64 to the outside. When the desired temperature is reached in the top portions of the producer, the oil burner is removed and the valve 74 is closed. Valve 68 in the pipe 66 which supplies air under pressure, and valve 69 in the pipe 67 which supplies steam are then partially opened, and a mixture of air and steam is admitted through the line 22. This mixture of air and steam passes through the pipes 23 and 24, the inner chambers of the headers, and the conduits in the heating plates between the tubes 9, the pipes 25 and 26, coupling 27, and pipes 28, 60, elbow 59, and vertical pipe 49, discharging onto the plate 70 by which it is deflected upwardly through the grate 48 and into the body of coke 50. This mixture is maintained sufficiently rich in air to maintain the temperature existing in the coke.

Valve 63 is now partially opened, and a small flow of oil is admitted to the still S from the oil supply line 36 and kept flowing strongly enough to keep the burner supply line 62 filled up to the cup 62', and a spray of oil escapes through the ring 61. This oil trickles down over the highly heated checker work and finally into the hot bed of coke, by which the oil is completely converted to gases. The supply of oil escaping through the spraying ring 61 is regulated in such manner that it is all partially burned up so that the coke supply is not diminished, but the flow is restricted sufficiently to prevent it from overflowing the coke chamber and flowing down into the line 71, since this would tend to lower the intensity of heat in the coke chamber. In conjunction with this, the mixture of air and steam supplied through the line 22 is held at such a point that a balanced heat condition prevails in the producer at all times.

With the construction described quite a latitude of temperature range is possible in the gases discharged from the producer through the pipe 56, and the chemical structure of the gas produced can be controlled to create the most desirable effect of such gas in the still on oil that is being cracked. For example, a large quantity of low temperature gas may be produced, or a smaller quantity of high temperature gas may be produced. In either case a proper working

degree of heat is maintained in the producer, the intensity of the heat in the gas chamber is varied to suit, and the chemical structure of the gas is varied accordingly. There are, however, practical limits to this temperature variation, as, for example, too high a temperature will produce lamp black in the gas which is undesirable, and too low a temperature will produce an objectionable amount of tar. An excessively high temperature may be avoided by reducing the flow of steam and air, and too low a temperature may be avoided by increasing the flow of steam and air. Also, if the coke volume becomes diminished, which is undesirable, this condition may be remedied by increasing the volume of residuum admitted; and if, on the other hand, the coke volume increases, which is also undesirable, this condition may be checked by decreasing the volume of residuum admitted. The actual amounts and rates of flow will, of course, vary in machines of differing sizes; but the proper volumes and rates of flow may be easily determined by experiment in any given machine by operators skilled in the art of petroleum distillation.

Having arrived at a desirable condition in the combustion cycle, the gases escaping through the pipe 64 will be found to be rich in hydrogen. When this condition is reached valve 58 is opened and valve 65 is closed. The trap 44 having been previously filled with some heavy fuel oil, the hot gases flowing downwardly through the pipe 45 bubble through the seal and upwardly into the pipe 32, thence up through the tubes 9 and outer chambers of the headers of the heating plates, being finally discharged into the cracking chamber (interior of the tank 5) through the discharge pipes 19. In flowing upwardly through the tubular chambers of the heating plates they heat the air and steam supply traveling downwardly through the heating plates to the producer. The air and steam supply during its downward travel also acts as a moderator of the temperature of the hot gases, and thereby effects a uniform distribution of heat to the oil in process flowing over the heating plates. After the apparatus has been operated for a short time, the tar liquefying from the hot gas lines in the cracking chamber trickles down through the pipe 32 and displaces the fuel oil in the seal 44. Thus, from this point on, the tar so produced serves as a seal for the gas.

The flow of feed stock from the supply line 36 is now gradually increased, and the volume of gas generated in the producer is correspondingly increased, until the necessary temperature is developed in the still S to warrant building the desired pressure. When this point is reached, a valve (not shown) in the pipe 36 (which acts both as a

supply pipe and as a conduit for the vapors and gases formed in the process) is closed, and the vapors produced in the still and the gas generated in the producer rapidly develop the desired pressure throughout the system. It is understood that the air and steam furnished through the lines 66 and 67 are from sources whose pressure is somewhat higher than the pressure desired in the cracking process.

After the desired pressure is acquired on the cacking system, the process is carried on continuously. The oil originally supplied to the spraying ring 61 in the producer is gradually replaced by the residuum of the cracking process, a part of this residuum being consumed in the producer, while the remainder, overflowing the cup-shaped upper end 62' of the spray supply pipe 62 flows downwardly through pipe 41 into the residuum tank 40, from which latter it is forced by the pressure in the system upwardly through pipes 20 and 21 into the outer chambers of the headers lying above the headers 12, flowing thence through the remaining heating plates in the upper portion of the cracking chamber, and being discharged through pipes 33, 34 and 35, and thence preferably following the course of the vapors through the balance of the system, but out of contact with the vapors, as disclosed in my former application, Serial No. 566,470, hereinbefore referred to.

The air and steam forced into the producer enter the heating plates at the top of the cracking chamber and travel through the entire series of heating plates all the way to the bottom, extracting heat therefrom, and during their further travel to the bottom of the producer extracting additional heat from the upflowing hot gases so that when they issue into the producer they approach the temperature of the hot gases generated in the latter and to that extent relieve the work of the producer. Any tar that is generated in the producer trickles down through the coke and the bottom of the producer chamber, and flows thence through the pipe 71 into the residuum tank 40, the valve 72 being open when the apparatus is operating. The producer and residuum tank are, of course, disposed at such relative heights that the normal working level of the residuum and tar in the residuum tank will be below the bottom of the producer.

The system is capable of continuous operation through long periods without requiring a shut-down for cleaning or repairs. It will be seen that, with the exception of the extraneous heat employed in bringing the producer initially up to the required temperature, the fuel for heat used in operating the system is almost wholly supplied by and from the material in process of distillation; the only exception being the relatively small

amount of fuel used to generate the heat furnished by the steam through the lines 67 and 22. The oil and residuum supplied to the producer are in just sufficient quantities to maintain the necessary combustion within the latter without appreciably drawing upon the body of coke; thus requiring renewal of the latter only at long periods.

From the foregoing it will also be seen 10 that the system operates as a single unit, generating, first from the oil in process and later from the residuum product of the cracking operation, a gas rich in hydrogen, which is utilized in two ways; first, to heat 15 up the inflowing air and steam and also the material in process flowing over the lower heating plates and, second, to mingle with the vapors and assist the cracking process. This described method and means of generating 20 such gas and its mode of utilization constitute the chief novel features of the present invention.

I claim—

1. A process of cracking oil, which consists 25 in distilling the oil in the form of a thin moving film under pressure in a still, simultaneously generating from the residual products of the distillation in a separate chamber a gas rich in hydrogen, and introducing 30 said gas into the presence of the vapors of distillation.

2. A process of cracking oil which consists 35 in distilling the oil in the form of a thin moving film under pressure in a still, simultaneously generating from the residual products of distillation in a separate chamber a gas rich in hydrogen, and introducing 40 said gas as it is generated into the presence of the vapors of distillation while the latter are under pressure.

3. A process of cracking oil, which consists 45 in distilling the oil in the form of a thin moving film under pressure in a still, simultaneously burning with the aid of restricted internal combustion residual products 50 of distillation in a separate chamber under the pressure existing in the still to generate a gas rich in hydrogen, and introducing said gas as it is generated into the presence of the vapors of distillation in said still while said vapors are under pressure.

4. A process of cracking oil, which consists 55 in distilling the oil in the form of a thin moving film under pressure in a still, simultaneously burning with the aid of restricted internal combustion residual products 60 of distillation in a separate chamber under the pressure existing in the still and in the presence of steam to generate a gas rich in hydrogen, and introducing said gas as it is generated into the presence of the vapors of distillation in said still while said vapors are under pressure.

5. A process of cracking oil, which consists 65 in distilling the oil under pressure in

a still, simultaneously generating from the residual products of the distillation by internal combustion thereof in a separate chamber and within restricted temperature limits a hot gas rich in hydrogen, transferring a 70 part of the heat of said gas to the oil in process of distillation out of contact with said oil, and then introducing said gas into the presence of the vapors of distillation while the latter are under pressure.

6. A process of cracking oil, which consists 75 in distilling the oil under pressure in a still, simultaneously generating from the residual products of distillation by internal combustion thereof in a separate chamber 80 and within restricted temperature limits and in the presence of hot air and steam a hot gas rich in hydrogen, transferring a part of the heat of said gas to the oil in process of distillation and to the said air and steam 85 out of contact with said oil, air and steam, and then introducing said gas into the presence of the vapors of distillation while the latter are under pressure.

7. A process of cracking oil, which consists 90 in distilling the oil under pressure in a still, simultaneously generating from a part of the residual products of distillation by internal combustion thereof in a separate chamber 95 and within restricted temperature limits under the pressure existing in the still a hot gas rich in hydrogen, transferring a part of the heat of said gas to the oil in process of distillation out of contact with said oil, introducing said gas into the presence 100 of the vapors of distillation while the latter are under pressure, and transferring heat from the remaining part of the residual products of distillation to the oil in process 105 of distillation.

8. A process of cracking oil, which consists 110 in distilling the oil under pressure in a still, simultaneously generating from a part of the residual products of distillation by internal combustion thereof in a separate chamber and within restricted temperature limits under the pressure existing in the still and in the presence of hot air and steam a hot gas rich in hydrogen, transferring a part 115 of the heat of said gas to the oil in process of distillation and to the said air and steam out of contact with said oil, air and steam, introducing said gas into the presence of the vapors of distillation while the latter are under pressure, and transferring heat from 120 the remaining part of the residual products of distillation to the oil in process of distillation and to the said air and steam.

9. In an apparatus for cracking oil, the combination of a pressure still, inclined heating plates in said still over which the oil flows progressively in a thin film a gas producer, means for supplying oil from said still to said producer for combustion in the latter, and means for conducting the gas 125 130

generated in said producer into said still and discharging it into the vapors of distillation in the latter.

10. In an apparatus for cracking oil, the combination of a pressure still, imperforate hollow heating elements therein, a gas producer, means for supplying oil from said still to said producer for combustion in the latter, and means for conducting the gas generated in said producer through said heating elements and discharging it thence into the vapors of distillation in said still.

11. In an apparatus for cracking oil, the combination of a pressure still, inclined heating plates in said still over which the oil flows progressively in a thin film, a gas producer, a pipe for conducting residual products of distillation from said still to said producer for combustion in the latter, and means for conducting the gas generated in said producer into the presence of the vapors generated in said still.

12. In an apparatus for cracking oil, the combination of a pressure still having imperforate hollow heating elements therein, a gas producer, a pipe for conducting residual products of distillation from said still to said producer for combustion in the latter, and means for conducting gas generated in said producer through heating elements of said still and discharging it thence into the vapors of distillation in the latter.

13. In an apparatus for cracking oil, the combination of a pressure still, inclined heating plates in said still over which the oil flows progressively in a thin film a gas producer, a residuum tank, a pipe connecting the bottom of said still with said residuum tank, a pipe operative to conduct a portion of the residuum to said producer for combustion in the latter, and means for conducting the gas generated in said producer into the presence of the vapors generated in said still.

14. In an apparatus for cracking oil, the combination of a pressure still having a residuum discharge opening in its bottom, a residuum tank beneath said still, a residuum discharge pipe connecting said tank and still and at its upper end surrounding the discharge opening in the latter, a gas producer, a pipe for conducting residuum to said producer for combustion in the latter, said last-named pipe having an upstanding portion located within said residuum discharge pipe and formed with an open upper end directly beneath the discharge opening in the bottom of said still, and means for conducting the gas generated in said producer into the presence of the vapors generated in said still.

15. In an apparatus for cracking oil, the combination of a pressure still, a residuum tank beneath said still, a residuum discharge pipe connecting the bottom of said still with

said tank, a gas producer, means for supplying oil from said still to said producer for combustion in the latter, a pipe for conducting the gas generated in said producer into said still, and an oil trap interposed in said last-named pipe.

16. In an apparatus for cracking oil, the combination of a pressure still, a residuum tank beneath said still, a residuum discharge pipe connecting the bottom of said still with said tank, an oil trap in said tank, a gas producer, means for conducting residuum to said producer for combustion therein, a pipe conducting gas generated in said producer into said trap, and a pipe conducting the said gas from said trap to said still.

17. In an apparatus for cracking oil, the combination of a pressure still having hollow heating elements therein, a residuum tank, a pipe connecting the bottom of said still with said tank, a gas producer, a pipe for conducting residuum to said producer for combustion therein, means for conducting gas generated in said producer through certain heating elements of said still and discharging it thence into the vapors of distillation in the latter, and means for conducting residuum from said tank into other heating elements of said still.

18. In an apparatus for cracking oil, the combination of a pressure still, inclined heating plates in said still over which the oil flows progressively in a thin film, a gas producer, means for supplying residual products of distillation from said still to said producer for combustion in the latter, means for supplying steam to said producer, and means for conducting the gas generated in said producer into the presence of the vapors generated in said still.

19. In an apparatus for cracking oil, the combination of a pressure still, inclined heating plates in said still over which the oil flows progressively in a thin film a gas producer, means for supplying residual products of distillation from said still to said producer for combustion in the latter, means for supplying steam and air under pressure to said producer, means for pre-heating said steam and air in its passage to said producer, and means for conducting the gas generated in said producer into the presence of the vapors generated in said still.

20. In an apparatus for cracking oil, the combination of a pressure still having hollow heating elements therein, a gas producer, means for supplying oil from said still to said producer for combustion in the latter, means for supplying a mixture of steam and air to one end of said hollow heating elements, a pipe for conducting said mixture from the other end of said heating elements to said producer, and a pipe for conducting the gas generated in said producer into the presence of the vapors generated in said

still; said last named pipe extending through said mixture conducting pipe.

21. In an apparatus for cracking oil, the combination of a pressure still, a gas producer, a residuum tank, a pipe connecting the bottom of said still with said residuum tank, a pipe operating to conduct a portion of the residuum to said producer for combustion in the latter, means for conducting the 10 gas generated in said producer into the presence of the vapors generated in said still, and a return flow pipe connecting said producer with said residuum tank.

22. In an apparatus for cracking oil, the combination of a pressure still, a gas producer, a residuum tank, a pipe connecting the bottom of said still with said residuum tank, a pipe operating to conduct a portion of the residuum from the bottom of said still to said producer for combustion in the latter, means for conducting the gas generated in said producer into the presence of the vapors generated in said still, and a return flow pipe connecting the bottom of said producer into said residuum tank. 15 20

FRANCIS M. HESS.
